UNITED STATES PATENT OFFICE.

GUSTAVUS MILLHISER, OF RICHMOND, VIRGINIA, ASSIGNOR TO THE MILLHISER MANUFACTURING COMPANY, OF SAME PLACE.

DESIGN FOR A TOBACCO-BAG.

SPECIFICATION forming part of Design No. 28,239, dated February 1, 1898.

Application filed December 11, 1897. Serial No. 661,562. Term of patent 14 years.

To all whom it may concern:

Be it known that I, GUSTAVUS MILLHISER, a citizen of the United States, residing at Richmond, in the county of Henrico and State of Virginia, have invented and produced a new and original Design for a Tobacco - Bag, of which the following is a specification, reference being had therein to the accompanying drawings, in which—

10 Figure 1 is a perspective view, Fig. 2 an edge view, and Fig. 3 a side elevation, of the bag.

As shown in the drawings, the leading or material feature of my design consists of a 15 tobacco-bag having two broad flat sides *a* opposite and parallel to each other, two vertical flat edge surfaces or sides *b* opposite each other and parallel, and a curved lower edge surface or side *c* connecting with and curving

into the said edge surfaces *b*, the curvature 20 of this lower edge surface being substantially that of a semicircle and its width being equal to that of the edge surface *b*, the edge surfaces *b* and *c* being perpendicular to the faces *a* and the upper end of the bag being open to 25 form the rectangular mouth *d*.

Having described my invention, what I claim as new, and desire to secure by Letters Patent, is—

The design for a tobacco-bag, substantially 30 as herein shown and described.

In testimony whereof I affix my signature in presence of two witnesses.

GUSTAVUS MILLHISER.
